UNITED STATES PATENT OFFICE

CONRAD A. CARBAUGH, OF DICKEYS MOUNTAIN, PENNSYLVANIA

ADJUSTING STOP FOR SAWMILL CARRIAGE HEAD BLOCKS

Application filed November 15, 1930. Serial No. 495,980.

This invention relates to improvements in the saw mill head block adjusting stop which constitutes the subject-matter of my co-pending application, filed August 6, 1929, serially numbered 383,915 and allowed June 13, 1930, Patent Number, 1,784,175, granted December 9, 1930, and which comprises a bracket secured to one of the saw mill carriage supporting beams, a guide carried by the bracket in close relation to the outer side of such beam, a stop bar mounted in the guide for vertical rectilinear movement into and out of position for contact by one of the head blocks, and a manually operable lever for the stop bar having its power end located outwardly of the other saw mill carriage supporting beam and having its load end connected to the stop bar.

The present invention has for one of its objects to provide a head block adjusting stop of the character stated which shall embody a bracket adapted to permit the adjusting stop to be used in connection with those saw mill carriages having power receder rails and in connection with those saw mill carriages not equipped with such rails.

The invention has for a further object to provide a head block adjusting stop wherein the bracket shall be of such form as to permit it to be secured to that saw mill carriage supporting beam opposite which the power receder rail is located without interfering with the operation of such rail, and wherein the bracket shall be adapted to support the stop bar for movement in a path so located with respect to the power receder rail as not to interfere with the operation of such rail and so located with respect to the path of movement of the knee receding means mounted on the carriage and adapted to be operated by said rail as to render it impossible for such means to contact with the stop bar.

The invention has for a further object to provide a bracket of the character stated which shall be simple, strong and durable, and which may be easily and quickly secured to the mentioned supporting beam for a saw mill carriage.

50 The invention has for a further object to

provide novel means for connecting the load end of the lever to the stop bar.

With the foregoing and other objects in view, the nature of which will appear as the description proceeds, the invention consists in the construction, combination and arrangement of parts hereinafter fully described and claimed, and illustrated in the accompanying drawings, wherein:—

Figure 1 is a transverse section through a saw mill carriage and the supporting beams of the same and showing my head block stop in applied position.

Figure 2 is a view in front elevation of the bracket and stop bar of the head block adjusting stop.

Figure 3 is a detail view of one of the links of the means for connecting the load end of the lever to the stop bar.

Figure 4 is a view in side elevation of a modified form of the head block adjusting stop.

Figure 5 is a view in front elevation of the head block adjusting stop shown in Figure 4.

Figure 6 is a view in side elevation of a further modified form of the head block adjusting stop.

Figure 7 is a view in front elevation of the bracket and stop bar of the head block adjusting stop shown in Figure 6.

Figure 8 is a view in side elevation of a still further modified form of the head block adjusting stop, and

Figure 9 is a view in front elevation of a fragmentary portion of the head block adjusting stop shown in Figure 8.

Referring in detail to the drawings, 10 designates a saw mill carriage, and 11 one of the head blocks of the carriage. 12 designates one of the axles of the carriage 10, and 13 and 14 designate the wheels of the carriage mounted upon this axle. The wheel 14 is shown as a flanged wheel engaging a flanged rail 15, while the wheel 13 is shown as a plain faced wheel engaging a flat rail 16. The rails 15 and 16 are mounted upon beams 17 and 17a. Mounted upon the head block 11 is a knee 19 which, after the log has been sawed up, together with the other

90

95

100

knee of the carriage is receded or moved back to such a position as to permit another log to be placed upon the head blocks. The means for receding the knees comprises a 5 rail 19a located outwardly of and parallel to the beam 17a, a bracket 19b carried by the carriage 10, and a roller 19c journaled on the bracket and supported thereby for movement in a path above and parallel to 10 the receder rail. The roller 19c is connected to the guide shaft 18 by gears, not shown, and the guide shaft is connected to the knees by pinions and racks, not shown. After the log has been cut up, the power receder rail 15 19a is moved upwardly into contact with the roller 19c, and this is done through the medium of the lever, not shown. The consequent rotation of the roller 19c and shaft 18, results in the knees of the carriage being 20 receded or moved back to such position as to permit another log to be placed upon the head blocks.

After the knees have been receded, the lever is released, resulting in the downward 25 movement of the power receder rail 19a and the throwing out of operation of the receding means. As the saw mill carriage and the knee receding means are of well-known construction, a further illustration and description 30 thereof are deemed unnecessary.

A supporting bar 20 which is located below and extends transversely of the beams 17 and 17a, is terminally secured to the beams, as at 20a. The bar 20 is provided with a 35 longitudinal series of openings 21, and a hanger 22 is secured to the bar by means of a bolt 22a passing through one of said openings. A pedal lever 23 which is located below the beams 17 and 17a and the bar 20, 40 and which extends transversely of the beams, is pivoted intermediate its ends to the lower end of the hanger 22 by a bolt 24. The lever 23 is provided with longitudinal series of openings 25, and the bolt 24 passes through 45 one of these openings. The lever 23 is provided at its power end with an upwardly extending arm 26 which is located outwardly of the beam 17 and which is provided at its upper end with a treadle 27. The load end 50 of the lever 23 extends outwardly beyond the beam 17a, and is upwardly bent, as at 28.

A bracket 29 which is secured to the beam 17a, comprises an angle bar 30 bolted, as at 55 31, to the lower and outer sides of this beam, a horizontal arm 32 extending outwardly from the lower side of the angle bar to a point beyond the power receder rail 19a, and a vertical arm 33 extending upwardly from the outer end of the arm 32 to a point above 60 the roller 19c. The arm 33 is provided in its upper end with an upwardly and inwardly inclined opening 34, and is provided at its outer side and below the opening with a boss 35 which is provided with an upwardly and 65 inwardly inclined opening 36 registering

with the opening 34. The apertured upper end of the arm 33 and the apertured boss 36 constitute a guide for a stop bar 37. The stop bar 37 is mounted in the openings 34 and 36 for rectilinear movement in an upwardly and inwardly inclined plane, to the end that its upper end will, when it is raised into active position, contact with the head block 11 at a point below and inwardly of the guide shaft 18. The bracket 29 clears 70 the power receder rail 19a, bracket 19b and roller 19c, and supports the stop bar 37 in such position that it will also clear these parts of the knee receding means and may be moved into operative position and out of 75 such position without contacting with such parts.

The bracket 29 is provided with ears 38 which extend downwardly from the arm 32 in alignment with the arm 33 and which are 80 provided with a vertical series of openings 39. A lever 40 is pivoted at one end to and between the ears 38 by a pin 41 which passes through a horizontal aligned pair of the openings 38. The lever extends upwardly and outwardly from its pivot 41 and its upper end is connected to the lower end of the stop bar 37 by a link 42. The upturned load end 28 of the lever 23 is connected to an intermediate point of the lever 95 40 by a link 43. The lever 40 is provided with a longitudinal series of openings 44, and the pivot 45 of the link 43 passes through one of these openings. The openings 39 of the ears 38 permit the vertical 100 shifting of the pivot 41 of the lever 40, and the openings 44 of the lever 40 permit the point of connection of the link 43 with the lever to be adjusted toward and away from the pivot 41, to the end that the extent of 105 the movement of the stop bar 37 as the result of the depression of the lever 23 may be varied, so as to adapt the head block adjusting stop for application to saw mill carriages of different size. A lug 46 is 110 secured to the stop bar 37, and is adapted to contact with the under side of the boss 35 to limit the movement of the stop bar in the direction of the head block 11. The links 42 and 43 may be of one piece or two 115 piece construction, as shown in Figures 3 and 5, respectively.

In the modified form of the head block adjusting stop shown in Figures 4 and 5, the bracket 29a comprises an angle bar 30a which consists of two members 47 connected by rivets 47a. The stop bar guide 48 is of inverted U-form in cross section, and the lever 40 is pivoted directly to the lower end of the stop bar. The guide 48 is secured to the outer side of the vertical bracket arm 33a, as at 49, and the upper side thereof inclines upwardly and inwardly to support the stop bar 37 in an upwardly and 120 inwardly inclined position. The guide 48 is 125 130

provided at its lower end with downwardly and outwardly inclined ears 38a to and between which the lower end of the lever 40 is pivoted, as at 50. The lever inclines upwardly and outwardly from its pivot, and is connected at its upper end to and between ears 51 extending downwardly and inwardly from the lower end of the stop bar 37. The load end of the pedal lever 23a is straight, and is connected by a link 52 to an intermediate point of the lever 40. The other parts of this head block adjusting stop are similar to the corresponding parts of the one shown in Figures 1 and 2, and are designated by similar reference characters.

The head block adjusting stop shown in Figures 6 and 7 differs from the one shown in Figures 4 and 5 merely in that the load end of the pedal lever 23a is connected directly to the lower end of the stop bar 37. To permit this direct connection, the load end portion of the lever is inclined upwardly and outwardly, as shown at 53, the upper end of such angular portion being connected by a pivot 54 to the lower end of the stop bar 27. The other parts of this head block adjusting stop are similar to the corresponding parts of the one shown in Figures 4 and 5 and are designated by corresponding reference characters.

The head block adjusting stops shown in Figures 1 to 7 are adapted for saw mill carriages having power receder rails, and the head block adjusting stop shown in Figures 8 and 9 is adapted for saw mill carriages not provided with power receder rails. This head block adjusting stop differs but slightly from those shown in Figures 6 and 7, the difference residing merely in omitting the angle bar 30a of the bracket 29a so as to permit the guide 48 to be arranged in close proximity to the beam 17a. The other parts of this head block adjusting stop are designated by the reference characters employed in connection with the corresponding parts of the head block adjusting stop shown in Figures 6 and 7.

When the lever 23 is depressed, the stop bar 37 will be shifted upwardly and inwardly to position its upper end in the path of movement of the head block 11, with the result that the movement of the head block is arrested, and the distance between it and the other head block of the saw mill carriage is reduced. If the stop bar 37 be retracted or allowed to move downwardly and outwardly, as it will under its own weight, the head block 11 will then move with the saw mill carriage. If it is desired to increase the distance between the two head blocks, the stop bar 37 is then shifted outwardly until after the head block 11 has passed the same, so as to arrange it in the path of the other head block.

The openings 21 and 25 permit the hanger

22 to be shifted nearer to or further from the treadle end of the lever 23 to thus change the leverage to shorten the length of the stroke.

From the foregoing description, taken in connection with the accompanying drawings, it will be apparent that I have provided novel, simple and highly efficient head block adjusting stops, that the head block adjusting stops may be manufactured and sold at comparatively low cost and easily and quickly applied, that three of the head block adjusting stops are adapted for application to saw mill carriages provided with power receder rails, and that the remaining head block adjusting stop is adapted for application to saw mill carriages not provided with power receder rails.

While I have illustrated a certain particular arrangement of parts, I do not wish to be limited thereto as it is obvious that these arrangements might be changed in many ways without departing from the spirit of the invention as defined in the appended claims.

I claim:

1. A head block adjusting stop, comprising a horizontal bracket arm adapted to be secured in an outwardly extended position to one of the track supporting beams for a saw mill carriage, a vertical bracket arm extended upwardly from the outer end of the horizontal bracket arm, a stop bar, a guide carried by the vertical bracket arm and supporting the stop bar for sliding movement in an upwardly and inwardly inclined plane, a lever pivoted to the supporting beams, and means connecting the lever to the lower end of the stop bar.

2. A head block adjusting stop, comprising a horizontal bracket arm adapted to be secured in an outwardly extended position to one of the track supporting beams for a saw mill carriage, a vertical bracket arm extended upwardly from the outer end of the horizontal bracket arm, a stop bar, a guide carried by the vertical bracket arm and supporting the stop bar for sliding movement in an upwardly and inwardly inclined plane, a lever pivoted between its ends to the supporting beams and having an angular load end and means connecting said end of the lever to the lower end of the stop bar.

3. A head block adjusting stop, comprising a horizontal bracket arm adapted to be secured in an outwardly extended position to one of the track supporting beams for a saw mill carriage, a vertical bracket arm extended upwardly from the outer end of the horizontal bracket arm, a stop bar, a guide carried by the vertical bracket arm and supporting the stop bar for sliding movement in an upwardly and inwardly inclined plane, and a lever pivoted between its

ends to the supported beams and having an angular load end pivoted directly to the lower end of the stop bar.

4. A head block adjusting stop, comprising a horizontal bracket arm adapted to be secured in an outwardly extended position to one of the track supporting beams for a saw mill carriage, a vertical bracket arm extended upwardly from the outer end of the horizontal bracket arm, a stop bar, a guide carried by the vertical bracket arm and supporting the stop bar for sliding movement in an upwardly and inwardly inclined plane, a lever pivoted to one of the bracket arms and to the lower end of the stop bar, a second lever pivoted between its ends to the supporting beams, and a link connected to the load end of said second lever and to said first lever at a point between the ends of the latter.

5. A head block adjusting stop, comprising a horizontal bracket arm adapted to be secured in an outwardly extended position to one of the track supporting beams for a saw mill carriage, a vertical bracket arm extended upwardly from the outer end of the horizontal bracket arm, a stop bar, a guide carried by the vertical bracket arm and supporting the stop bar for sliding movement in an upwardly and inwardly inclined plane, a lever pivoted at one end to one of the bracket arms, a link connecting the other end of the lever to the lower end of the stop bar, a second lever pivoted between its ends to the supporting bars, and a link connected to the load end of said second lever and to an intermediate point of said first lever.

6. A head block adjusting stop, comprising a horizontal bracket arm adapted to be secured in an outwardly extended position to one of the track supporting beams for a saw mill carriage, a vertical bracket arm extended upwardly from the outer end of the horizontal bracket arm, a stop bar, a guide carried by the vertical bracket arm and supporting the stop bar for sliding movement in an upwardly and inwardly inclined plane, a lever having an adjustable connection at one end with one of the bracket arms, a link connected to the other end of the lever and to the lower end of the stop bar, a second lever pivoted between its ends to the supporting beams, a link connected to the load end of said second lever and adjustably connected to said first lever.

7. A head block adjusting stop, comprising a horizontal bracket arm adapted to be secured in an outwardly extended position to one of the track supporting beams for a saw mill carriage, a vertical bracket arm extended upwardly from the outer end of the horizontal bracket arm, a stop bar, a guide carried by the vertical bracket arm, and supporting the stop bar for sliding

movement in an upwardly and inwardly inclined plane, and means for operating the stop bar.

8. A head block adjusting stop, comprising a horizontal bracket arm adapted to be secured in an outwardly extended position to one of the track supporting beams for a saw mill carriage, a vertical bracket arm extended upwardly from the outer end of the horizontal bracket arm and provided in its upper end with an upwardly and inwardly inclined opening, a boss on the outer end of the vertical bracket arm and provided with an upwardly and inwardly inclined opening registering with said first opening, a stop bar slidably mounted in said openings, and means for operating the stop bar.

9. A head block adjusting stop, comprising a horizontal bracket arm adapted to be secured in an outwardly extending position to one of the track supporting beams for a saw mill carriage, a vertical bracket arm extending upwardly from the outer end of the horizontal bracket arm, a guide of inverted U-form in cross section secured to the outer side of the vertical bracket arm and having an upwardly and inwardly inclined top wall, a stop bar slidably supported by the guide, and means for operating the stop bar.

10. A head block adjusting stop, comprising an angle bar adapted to be secured to one of the track supporting beams for a saw mill carriage, a horizontal bracket arm extended outwardly from the bar, a vertical bracket arm extended upwardly from the outer end of the horizontal arm, a stop bar slidably supported on the horizontal bracket arm, and means for operating the stop bar.

In testimony whereof I hereunto affix my signature.

CONRAD A. CARBAUGH.
